His Attorney.

UNITED STATES PATENT OFFICE.

LEO J. DOTY, OF KANSAS CITY, MISSOURI.

SAFETY FILM REEL.

Application filed July 21, 1919. Serial No. 312,156.

To all whom it may concern:

Be it known that I, LEO J. DOTY, a citizen of the United States, residing at Kansas City, in the county of Jackson and State of Missouri, have invented a certain new and useful Improvement in Safety Film Reels, of which the following is a specification.

My invention relates to improvements in safety film reels.

10 My invention provides a novel hoop which is adapted to be affixed releasably to a film reel so as to completely cover the outer side of a film held on the reel and which will protect the film from catching fire.

15 The novel features of my invention are hereinafter fully described and claimed.

In the accompanying drawing which illustrates the preferred embodiment of my invention,

20 Fig. 1 is an end view partly broken away of a reel provided with my improvement.

Fig. 2 is a sectional view on the line 2—2 of Fig. 1.

25 Fig. 3 is a perspective view of a portion of the reel, showing the releasable locking means.

Fig. 4 is a perspective view of another portion of the reel, showing the manner in which the hoop members are hinged together.

30 Fig. 5 is a perspective view of one of the collars.

Fig. 6 is a perspective view of the hub.

Similar reference characters designate 35 similar parts in the different views.

30 1 designates each of two heads of a drum which has a hub 2 having its ends abutting respectively against the inner sides of the heads and which has fitted in it two collars 3 each having a peripheral extension 4 fitted in the adjacent one of two recesses 5 provided one in each end of the drum. The drum is provided with a longitudinal slot 6 adapted to receive one end of a moving picture film, not shown.

45 Mounted concentrically in the drum hub 2 is a central tubular axle 7 the ends of which abut respectively against the inner sides of the heads 1. The latter are provided each with a central opening 8 which is of the same size and in alignment with the hole in the axle 7 and which is adapted to receive the shaft, not shown, which supports the reel in operative position.

50 Rivets or bolts 9 which have shouldered portions abutting against the inner sides of

the collars 3 extend through the collars and the heads 1, being riveted to the latter, and thereby holding the parts together.

For covering and protecting the film carried by the drum, when the film is not in use, I provide a hoop which is expandable and contractible so as to be slipped on and off the heads 1, and which is composed, preferably of two members 10 and 11 which have one set of ends overlapping, as shown in Fig. 4, said set of ends being hinged together by a link 12, the ends of which are respectively pivoted to two cleats 13 respectively secured to the outer sides of the members 10 and 11. By connecting the members 10 and 11 with the link 12, pivoted thereto at a substantial distance from the adjacent ends of said members, such ends will be swung widely apart in the open position 75 of the hook, thereby enabling the reel to be inserted therein more readily than would be the case if an ordinary pintle hinge connection were provided.

The other set of ends of the members 10 and 11 are adapted, when the hoop is in the closed position shown in Fig. 3, to overlap, laid overlapping ends being releasably held in the closed position by means of a locking cam lever 14, which is pivoted to 85 one end of a link 15, the other end of which is pivoted to a cleat 16 attached to the outer side of the member 11. The locking hook 14 is adapted for releasable engagement with one end of a link 17, the other end of which is pivoted to a cleat 18 attached to the outer side of the member 10.

Each member 10 and 11 is provided at opposite side edges with inwardly extending flanges 19, adapted to respectively embrace 90 the outer sides of the heads 1.

Each of the members 10 and 11 is preferably provided at its opposite edges with two grooves 20 adapted to respectively receive the outer edges of the heads 1, whereby 100 the heads are held apart.

In the operation of my invention, after the film has been placed on the hub 2, the hoop members 10 and 11 are fitted on the edges of the heads 1, so that the free ends of said members overlap, as shown in Figs. 1 and 3, after which the locking lever 14 is hooked through the link 17 and then turned to the locking position, shown in Figs. 1 and 3, thereby drawing together and holding the members 10 and 11 firmly on the drum and completely covering the outer

side of the film. Each head 1 is imperforate between the peripheries thereof and the hub 2, so that no spark or flame can reach the film through the closed heads. The heads 5 are preferably of relatively fire proof material, such as sheet metal, steel or brass. The members 10 and 11 are also of fire protective material, such as sheet steel. When fitted on the heads 1, the members 10 and 10 11 form therewith a tight fireproof covering for the film. The holes 8 in the heads are of the same size as the opening 2 of the 15 axle 7. The ends of the latter abutting against the heads prevents the entrance into the hub 2, at the outer side of the axle 7 of any sparks or flames. By employing the two links 15 and 17, a cam lever 14 may be utilized for fastening together the free ends of the members 10 and 11. By 20 the use of a cam lever, the members 10 and 11 are drawn forcibly together in the locking operation and are held securely locked in the closed position.

To use the film, it is but necessary to release the locking lever 14 from the link 17, 25 after which the members 10 and 11 may be swung to the open position and removed

from the heads 1. As shown in Fig. 1, the overlapping ends of the members 10 and 11 are flush with each other on their inner 30 sides, whereby no projecting surfaces are present to scratch or otherwise injure the film carried on the reel.

I do not limit my invention to the structure shown and described, as modifications, 35 within the scope of the appended claim, may be made without departing from the spirit of my invention.

What I claim is:—

A safety film reel cover comprising two 40 members having means for embracing the edges of the heads of a film reel and having one set of ends which overlap each other hinged together, the other set of ends being adapted to overlap each other in the 45 closed position, said members where they overlap having their inner surfaces flush with each other, and means for releasably locking together the free ends of said members, substantially as set forth. 50

In testimony whereof I have signed my name to this specification.

LEO J. DOTY.
